CONVEYER MECHANISM

Fred J. Wright, Powell, Ohio, assignor to The Jeffrey Manufacturing Company, a corporation of Ohio

Application May 6, 1941, Serial No. 392,086

5 Claims.

(Cl. 22—20)

The present invention relates to improvements in conveyer systems particularly adapted for use in foundry installations wherein moving molds are to be filled with molten metal, although said invention may have a general application.

One of the objects of the present invention is the provision of improved and efficient mechanism for intermittently moving a train of carriers along a track on which such train is adapted to travel, so that the ladle containing molten metal may be suspended from a stationary support and so that pouring may be effected while the flask containing the mold to be filled with molten metal, may be supported on a carrier while the latter is stationary on the supporting and guiding track.

Another object of the invention is the provision of hydraulic mechanism for moving a carrier along a track and of a hydraulic system of control to effect gradual stopping of the carrier in a predetermined position.

A further object of the invention is the provision of hydraulic mechanism for moving a carrier a predetermined distance in a predetermined period of time.

Another object of the invention is the provision of hydraulic motor mechanism adapted to move one carrier from one position to another and automatically return to initial position in readiness for moving another carrier from one position to another.

A further object of the invention is the provision of a hydraulic motor and automatic means for controlling the same including a volume control to effect regulation of the speed of operation of the motor.

Another object of the invention is the provision of hydraulic mechanism for operating carriers intermittently along a track and of electro-hydraulic system of control operable at will by attendants adjacent the carriers.

A further object of the invention is the provision of automatic mechanism for intermittently moving a train of carriers at predetermined time intervals to enable the carriers to be stationary one after another at the pouring station each for a predetermined definite period of time, to enable the molten metal in the pouring ladle to be emptied into the molds before such molten metal tends to cool.

Another object of the invention is the provision of a electro-hydraulic control system for a multiplicity of trains of carriers including two motor driven pumps and means for operating

them so that either or both pumps may be connected to all the hydraulic motors for individually operating the trains in a foundry installation.

5 Other objects of the invention will appear hereinafter, the novel features and combinations being set forth in the claims hereto appended.

In the accompanying drawings,

Fig. 1 is a plan view of an endless mold conveyer comprising a train of platform carriers;

Fig. 2 is a sectional elevation taken on the line 2—2 of Fig. 1, looking in the direction of the arrows;

Fig. 3 is an elevational view of a portion of 15 the endless mold conveyer shown in Fig. 1 with the intermittently actuating hydraulic mechanism applied thereto;

Fig. 4 is a transverse sectional elevation taken on the line 4—4 of Fig. 1, looking in the direction 20 of the arrows;

Fig. 5 is an enlarged elevation of spring-pressed pawl actuating mechanism associated with abutments mounted on the wheeled mold flat cars or carriers shown in Fig. 3;

25 Fig. 6 is a sectional elevation taken on the line 6—6 of Fig. 5, looking in the direction of the arrows;

Fig. 7 is a longitudinal sectional view of the 30 hydraulic actuating motor including means for decelerating the plunger for a predetermined distance and speed at the limit of its car actuating stroke shown in dotted lines in Fig. 3;

Fig. 8 is a longitudinal view of a modified hydraulic motor including variable means for adjusting the length and speed of deceleration at the limit of its car actuating stroke;

Fig. 9 is a plan view of the electric limit switch shown at the right-hand end of Fig. 3;

Fig. 10 is a sectional elevation of the limit 40 switch shown in plan in Fig. 9;

Fig. 11 shows a wiring and piping diagram including the electric circuits and connecting and hydraulic instruments for controlling the hydraulic actuating motor shown in dotted lines 45 in Fig. 3;

Fig. 12 is a sectional elevation of the electromagnetic valve mechanism for direct control of the hydraulic motor as diagrammatically illustrated in Fig. 11;

50 Fig. 13 is a sectional elevation of the volume control valve shown diagrammatically in Fig. 11 in the piping system; and

Fig. 14 is a wiring diagram illustrating two separate electric pump-operating motors either or both of which may be used in a system for

controlling any one or more of a plurality of hydraulic actuating motors each associated with a separate and independent train of mold carrying flat cars.

In Fig. 1 of the accompanying drawings is shown a plan view of a mold conveyer 15 comprising a train of platform cars or carriers 16 each comprising two pairs of wheels 17, 17 engaging and traveling along endless rails 18 and 19. The endless track comprising the rails 18 and 19 is supported in elevated position relative to the foundry floor 20 by means of spaced vertical supports 21, 21 connected by the floor cross-pieces 22 and the elevated cross-pieces 23, as shown in Figs. 2 and 3.

To the upper ends of the vertical supporting standards 21, 21, as shown in Fig. 2, are secured the longitudinal cover plates 24, 24 which extend inwardly over the tops of the wheels 17 of the flat cars or carriers 16.

Each carrier 16 comprises a platform 25 for receiving the foundry mold flasks. Each platform 25 is secured to the top of its truck frame 26 which in turn is secured to the axles 27 on the ends of which are journaled the track engaging wheels 17. Also secured to the axles 27 as well as to the truck frame 26 is an elongated supporting frame comprising upper and lower horizontal straps 28, 29, as shown in Fig. 3. Journaled to the ends of the suspended frame comprising the straps 28, 29 are rollers 30, 31 which are adapted to rotate on vertical axes in position to engage abutment plates 32, 33 which are approximately semi-circular in shape and secured to the cross-pieces 23 of the track supporting framework. It will be seen by referring to Figs. 1 and 3 that each car carrier 16 is provided with two of the rollers 30, 31 and that these rollers engage the semi-circular abutment plates 32 and 33 when the cars or carriers travel around the semi-circular ends of the endless track.

As shown in Fig. 3, coupling members 34, 34 are pivotally connected on the vertical axes of the rollers 30, 31 between the horizontal straps 28, 29 of one car or carrier and the horizontal straps 28, 29 of the next adjacent carrier. Each coupling member comprises bifurcated end members 35, 35 rigidly connected by the rod 36. The bifurcated members 35, 35 are each provided with curved abutment portions 37 in position to be engaged by the actuating pawl 38 which is pivotally connected at 39 to the outer end of the piston rod 40 of the elongated hydraulic motor 41 which comprises the cylinder 41.

As shown in Figs. 3 and 4, the hydraulic cylinder 41 is supported on a cross-piece 23' on which are mounted the inwardly extending channels 42, 42 for supporting the rails 18 and 19 at the same elevation at which they are supported by cross-piece 23 in Fig. 2. As shown in Fig. 4, the hydraulic cylinder 41 is supported on the cross-piece 23' intermediate the inner ends of the channels 42, 42.

A series of cross-pieces 23' may be provided between the various pairs of vertical supports 21, 21 to support the longitudinal plate 43, and the hydraulic cylinder 41 may be secured to such plate as well as the upper transverse or cross-pieces 43'. On the longitudinal plate 43 are mounted spaced-apart channels 44, 44 with their flanges directed toward each other as viewed in Fig. 6, to provide a trackway for the wheels 45, 45 of a carriage 46 connected to the front end of the piston rod 40.

As shown in Figs. 3 and 5, a spring 47 is mounted on the carriage 46 in position to engage the under side of the pawl 38 which is pivoted at 39 to the carriage 46.

When the piston rod 40 is retracted, the pawl 38 will occupy the dotted line position 38' shown in Fig. 3, and when the piston rod is moved outwardly or toward the right, as viewed in Fig. 3, the upper and outer end of the pawl 38 will engage the curved abutment 37 of the coupling 34 and move the whole endless train of flat cars a distance equal to slightly more than the length of the platform of each car. When the piston rod 40 is retracted or moved toward the left, as viewed in Fig. 3, the pawl 38 will engage the lower side of the next adjacent abutment 37 and pass under the same as permitted by the spring 47. In other words, when the plunger is retracted the spring 47 will permit a downward yielding movement of the pawl 38 under the abutments 37 at the end portions of the couplings 34.

In Fig. 7 I have shown one form of elongated hydraulic reciprocating motor which may be used for reciprocating the pawl 38 along the track formed by the channels 44, 44 shown in Fig. 6. The left-hand end of the hydraulic cylinder 41 as viewed in Fig. 7 may be closed by the cap 48, and a cylinder head 49 may be welded to the other end of the cylinder 41. A bushing 50 may be seated in the cylinder head 49 and a gland 51 used to close the right-hand end of the cylinder head 49 and to hold in place the packing 52. A lubricant seal 53 may also be provided between the packing gland 51 and the piston rod 40.

A fitting 54 for an opening through the cap 48 may be provided for connecting the supply pipe 55 to the interior of the cylinder 41 back of the piston 56 which is provided with a cylindrical recess 57 for receiving the spring 58. The piston rod 40 is of reduced diameter at 59 to provide a shoulder at 60 for receiving the spring retained deceleration ring 61 which is of such diameter as to be adapted to fit into the annular recess 62 in the piston 56. The piston rod 40 is further reduced in diameter at 63 to fit into an opening of the same diameter in the piston 56, and the portion 63 of reduced diameter is pinned at 64 to the piston 56.

By means of a fitting 65 the pipe 66 is connected through a screw-threaded opening in the cylinder head 49 to the interior of the cylinder 41. When the pressure medium in the pipe 55 flows into the cylinder 41 to the left of the piston 56, as viewed in Fig. 7, the piston rod 40 will be moved toward the right to actuate the pawl 38 and thereby effect movement of the train of cars approximately one car length. As the piston 56 moves toward the right as viewed in Fig. 7, the oil or other pressure medium will flow out through the pipe 66.

When the piston 56 approaches the limit of its stroke as illustrated in dotted lines in Fig. 7, the spring retained deceleration ring 61 first engages the annular shoulder 67 at the inner end of the cylinder head 49 thereby trapping the remaining hydraulic medium in the right-hand end of the cylinder 41 as viewed in Fig. 7. The trapped hydraulic medium will then, by continued forward movement of the piston, be forced through a series of circumferentially spaced perforations 68, 68, thereby causing a throttling or dash-pot action to the movement of the piston 56 toward the annular shoulder 67. When the inner end of the piston 56 engages the annular shoulder 67, the latter acts 75 as an abutment stop, and in this position the

spring retained deceleration ring 61 will be located in the annular recess 62.

When the hydraulic motor 241 is to be reversed, the de-energization of the solenoid 139 of Fig. 12 will cause the spring 141 to move the valve 143 up so that the pipe 55 will be connected to the exhaust or return pipe 138. The supply pressure in the pipe 66 will then act on the retained deceleration ring 61 to release the same from the annular shoulder 67 and move the piston 56 toward the left as viewed in Fig. 7. As soon as the ring 61 is released from the annular shoulder 67 full hydraulic pressure is exerted on the inner end of the piston 56 and consequently the piston moves quickly toward the left from its limit shown in dotted lines in Fig. 7. It should be noted that the ring 61 is appreciably less in diameter than the inner diameter of the cylinder 41 and therefore from the time the recess 62 leaves the ring 61 until the latter is engaged by the annular shoulder 60, the hydraulic liquid is free to flow past the periphery of the ring 61 as permitted by the yielding of the spring 58. In other words, the perforations 68 act as restricted passageways only when the piston is approaching its limit at the head end of the cylinder so that forward movement of the endless train may be stopped gradually. The return stroke of the plunger 40 is started quickly and continues until stopped by the piston 56 abutting against the inner surface of the cap 48.

Fig. 8 shows a modification 241' of the hydraulic reciprocating motor 241 connected to the pawl 38, as shown in Fig. 3. The cylinder 41' is closed at its left-hand end, as viewed in Fig. 8, by means of the cap 48', and by means of the fitting 54' the pipe 55' is connected to the interior of the cylinder 41' back of the piston 56'. The other end of the cylinder 41' is closed by the cylinder head 49', and the piston rod 40' extends through a packing 52' held in place by the packing gland 51' which is secured to the outer end of the cylinder head 49'.

The inner end of the piston rod 40' is of reduced diameter and screw-threaded as shown at 69. An abutment collar 70 fits against an annular shoulder 71 at the inner end of the piston rod 40', and is secured to the latter by means of a pin 72.

Screw-threaded on to the rod 69 is an auxiliary piston 73 which is held in adjusted position by means of the lock nut 74. The rod 69 is also screw-threaded into the main piston 56' and is held in adjusted position by means of the lock nut 75.

When the supply pressure medium enters the cylinder 41' through the pipe 55', the spaced-apart pistons 56' and 73 will start moving toward the right, as viewed in Fig. 8, and the liquid in the cylinder 41' will then be free to pass through the opening 76 to the pipe 77. It will be seen that the fitting 78 connects the pipe 77 to the chamber 79 of a chest 80 which is secured to the exterior of the cylinder 41'.

Spaced-apart openings are provided at 81 and 82 between the interior of the cylinder 41' and the chamber 79. Needle valves 83 and 84 are carried at the inner ends of screws 85, 86 which are screw-threaded through the outer wall of the chest 80 and secured in adjusted positions by the lock nuts 87 and 88.

When the pistons 56' and 73 first start toward the right, as viewed in Fig. 8, from their full line positions, the liquid in advance thereof may pass through all three openings 76, 81 and 82, but

when the piston 73 passes the opening 76 the liquid in advance of the piston 73 may then pass through only the openings 81 and 82 into the chamber 79 and thence to the pipe 77.

After the piston 73 passes beyond the port 76, the liquid between the pistons will tend to move bodily therewith. As the piston 73 moves toward the right or toward the port 81 the liquid flow through the ports 81 and 82 will be restricted and therefore the movement of the piston rod 40' will be slowed down. The extent to which the speed of movement of the piston rod 40' toward the right will be reduced, will depend upon the positioning of the needle valves 83 and 84 in restricting the passage of the liquid through the ports 81 and 82 to the chamber 79.

When the piston 73 passes the port 81 there will be still further reduction in speed because then the liquid in advance of the piston 73 may pass only through the port 82, such flow being restricted by the position of the needle valve 84. When the piston rod 40' reaches the right-hand limit of its stroke, as shown in dotted lines in Fig. 8, the collar 70 will abut against the annular shoulder 89 at the inner end of the cylinder head 49'. The engagement by the collar 70 with the annular shoulder 89 will be a positive limit stop for the actuating stroke of the piston rod 40', thereby positively limiting the extent to which the pawl 38 may be moved toward the right, as viewed in Fig. 3.

In order to avoid any sticking of the abutment collar 70 in its position against the annular shoulder 89 by reason of the formation of a vacuum, I have provided a plurality of circumferentially spaced grooves 90, 90 in the cylinder head 49' adjacent the annular shoulder 89. The grooves 90 are in communication with ports 91, 92 between which is located a spring-pressed ball check valve 93 held in position by the screw cap 94, as shown in Fig. 8. As the abutment collar 70 moves toward the annular shoulder 89, the passageway between the ports 91 and 92 will be retained closed by the ball check valve 93. However, when the piston rod 40' is moved toward the left, as viewed in Fig. 8, the check valve 93 permits flow from the chamber 79 through ports 91 and 92 into the grooves 90, thereby permitting rapid movement of the piston rod 40' to the left as viewed in Fig. 8. The diameter of the abutment collar 70 is appreciably less than the inner diameter of the cylinder 41' and consequently as soon as the collar 70 is released from the annular shoulder 89 the effective return stroke pressure will be on the right-hand side of the piston 73, the flow thereto being not only through the port 82 but also past the check valve 93 and through the port 91. When the piston 73 moves to the left as viewed in Fig. 8 the flow will be through the ports 81, 82, 91 and when the piston 73 moves to the left of the port 76 the flow will be through all the ports 76, 81, 82, 91.

Under some circumstances, as hereinafter more fully explained, it may be desirable to vary the length and speed of deceleration at the limit of the car actuating stroke of the plunger 40', depending upon the loads on the cars and time required for the pouring of the metal from the ladle into the molds in the flasks on the platforms 25 of the cars of the endless train. The length of the forward actuating stroke of the plunger 40' is predetermined by the distance of the abutment collar 70 from the annular shoulder 89 but the beginning of the deceleration period may be varied by adjustment of the piston 73 along

the screw-threaded rod 89. When in adjusted position it may be locked there by tightening the nut 74 against the same.

The closer to the collar 70 the piston 73 is located the sooner the deceleration period will begin and the longer the completion of the stroke from beginning to end will take. The closer to the piston 56 the piston 73 is located the more delayed will be the beginning of the deceleration but the completion of the full stroke will take less time.

After the reciprocating hydraulic motor 261 has been assembled to have a predetermined length of deceleration and a forward actuating stroke in a predetermined time, further refinements in the time of deceleration may be made by adjusting the needle valves 83 and 84. In any event the time of the return stroke may be predetermined so as to give the operators of the ladle plenty of time to effect pouring of the molten metal into the molds in the flasks on the platforms 25 before the train is moved forward another car length.

Referring now to the wiring and piping diagram illustrated in Fig. 11, I will describe the automatic mechanism for controlling the hydraulic reciprocating motor for intermittently actuating the foundry flask carriers. When the main line switch 95 is closed, the mains 96, 97 and 98 may be connected to the source of three-phase alternating current supply. The mains 96, 97, 98 are connected by the branch conductors 99, 100 and 101 to the switch 102 for controlling the electric motor 103 which is coupled to a hydraulic pump 104 to drive the latter. The alternating current supply mains are also connected by means of the main line switch 105 through the branch conductors 106, 107 and 108 to the switch 109 for controlling the electric motor 110 which is coupled to the hydraulic pump 111 to drive the latter.

By means of a transformer 112 two of the three-phase mains, namely, those designated 97 and 98, are connected to a controlling circuit comprising the conductors 113 and 114.

When it is desired to effect a closure of the motor switch 102, the push button switch 115 is pressed to closed position, whereupon a circuit will be established from the secondary of the transformer 112, which circuit may be traced from the conductor 113 through conductor 116, solenoid 117, conductor 118, switch 119, conductor 119, closed push button switch 120, conductor 129 and through conductor 114 back to the other terminal of the secondary of the transformer 112. The energization of the solenoid 117 will cause it to pull up its plunger 121 to effect closure of the motor switch 102, whereupon the electric motor 103 will be rotated and the hydraulic pump 104 driven.

The solenoid 122 is in parallel with the solenoid 117 and therefore when the solenoid 117 is energized, the solenoid 122 will also be energized. The energization of the solenoid 122 will effect lifting of the plunger 123 to cause the closure of the switch 124. The electric lamp 125 is in parallelism with the solenoids 117 and 122 and therefore when the latter are energized, the lamp 125 will give a signal that the electric motor 103 is rotating and that the pump 104 is being operated.

The switch 124 comprises two sets of contacts 126 and 127. Both sets of contacts will be closed when the plunger 123 is pulled up. The connection of the contacts 126 will effect a holding cir-

cuit by way of the conductors 128 and 129 through the push button switch 120. It will thus be seen that immediately after the push button switch 115 is closed, the contacts 126 will be connected and the holding circuit established through the push button switch 120. Release of the push button switch 115 will therefore not disturb the closure of the switch 102. After the push button switch 115 is released and moves to open position, continued energization of the solenoids 117 and 122 depends upon continued closure of the push button switch 120. Therefore, when it is desired to stop the operation of the pump 104, the push button switch 120 is pressed to open position, whereupon the switches 102 and 124 will be automatically opened and the electric light 125 will go out, thereby giving the signal that the pump 104 is no longer operating.

20 The pump 104 is connected by means of a suction pipe 130 to a supply tank 131. The pump 104 is also connected to a supply pipe 132 between which and the return pipe 133 is located a relief pressure valve 134 which is adapted to establish a by-pass for the pump when the pressure in the supply pipe 132 exceeds a predetermined maximum.

25 The supply pipe 132 is connected by means of the pipe 132' through the volume control mechanism 135 to the pipe 136. The pipe 136 is connected to an electro-magnetically operated valve 137 shown in sectional elevation in Fig. 12. The pipes 55 and 66 of Fig. 7 are shown in Fig. 11 connected respectively to the electro-magnetic valve 137 and the pipe 136. A return pipe 138 connects the electro-magnetic valve to the pipe 133 leading back to the tank 131.

30 When the solenoid 139 shown in Fig. 12 is energized, the plunger 140 will be pulled down against the action of the spring 141 to lower the valve pistons 142 and 143 to establish communication between the pressure pipe 136 and the pipe 55. Both sides of the piston 56 in the hydraulic motor cylinder 41 will then be connected to the pressure side of the pump 104. However, on account of the piston rod 40, the pressure area at the left-hand side of the piston 56 will be greater than the pressure area on the right-hand side thereof, as viewed in Figs. 7 and 11. It will therefore be seen that when the solenoid 139 of 35 Fig. 12 is energized, the piston rod 40 will be moved toward the right, as viewed in Fig. 3, to effect movement of the pawl 38 against the abutment 37 to move the train of cars 16 approximately one car length.

40 When the carriage 46 carrying the pawl 38 reaches the end of the track 44, 44, the right-hand end of the carriage 46 will strike against the roller 144 of the limit switch 145, effecting opening of the latter.

45 As shown in Fig. 10, the roller 144 is carried by an arm 146 which is pivoted at 147 to a bracket 148 mounted on the base 149 which carries the spaced-apart electric contacts 150, 151. The pivoted arm 146 is connected to a metal blade 152 adapted to connect the contacts 150 and 151. When the carriage 46 strikes the roller 144, the arm 146 will be moved in a clockwise direction as viewed in Fig. 10, to effect lifting of the switch blade 152 against the action of the spring 153 and consequently the limit switch 145 will be opened to effect de-energization of the valve operating solenoid 139 shown in Fig. 12. When the solenoid 139 is de-energized, the spring 141 will 50 return the valve 137 to its position shown in Fig.

12, and consequently the pressure pipe 136 will be cut off from the supply pipe 55. Pressure will remain between the supply pipe 136 and the pipe 66 on the piston 56 at the right-hand side thereof, as viewed in Fig. 11, and the piston rod 40 will therefore be moved back to its initial position, and this movement will effect movement of the pawl 38 back to its dotted line position illustrated at 38' in Fig. 3. During the return stroke of the piston 56, the pipe 55 will be connected to the pipe 138 through the valve structure 131 shown in Figs. 12.

The circuits and connections for effecting automatic reversal of the hydraulic actuating motor 241 when the limit switch 145 is automatically opened, are shown in Fig. 11. The limit switch contacts 150 and 151 are respectively connected to the conductors 150' and 151'. The conductor 150' is connected through the contacts 127 to the conductor 154 which is connected to the terminal 114 of the secondary of the transformer 112.

The station for loading the molding flasks on to the platforms 25 is preferably located at the left-hand end of the endless mold conveyer shown in Fig. 1. This loading station is designated LS and adjacent the same, within reach of the attendant, are two push button switches, one designated 155 being normally open, and the other designated 156 being normally closed.

After a flat car 16 has been moved approximately two car lengths from its loading station LS it will occupy the pouring station PS and at the latter station is located a normally closed emergency push button switch 157. A signal lamp 158 is located adjacent the loading station LS, and another signal lamp 159 is located adjacent the pouring station PS. During the return stroke of the piston rod 40 of the hydraulic motor 241, pouring of the molten-metal from the ladle may be effected into the flask on the platform 25 at the pouring station. The ladle may therefore be suspended from a stationary support, no trolley being necessary for movement of the ladle during pouring because pouring is effected while the flask is on a platform 25 which is stationary during the pouring period. The flat cars 16 are moved forwardly to the pouring station one after another and are then moved away therefrom in the direction of the arrow 160. The unloading station US is approached when the flat cars are moving in the direction of the arrow 161. By this time the metal is sufficiently cooled so that the flasks may be inverted and the contents dumped on to a grating at the unloading station US separate from the mold conveyer 15, for the purpose of shaking out the castings and separating the molding sand therefrom.

Reverting to Fig. 11 it will be seen that the signal lamps 158 and 159 respectively located at the loading station LS and the pouring station PS, as shown in Fig. 1, are connected in parallel with each other and in parallel with the solenoid 172. When the push button switch 155 at the loading station LS is closed, a circuit will be established through conductors 113, 163, 164, solenoid 165, conductor 166, push button switch 155, conductor 167, emergency push button switch 156 at the loading station LS, emergency push button switch 157 at the pouring station PS, conductor 151', limit switch 145, conductor 150', contacts 127, and conductor 154 to con-

ductor 114 at the other terminal of the secondary of the transformer 112.

Energization of the solenoid 165 will effect lifting of the plunger 168 and the closing of the contacts 169 and 170. The closure of the contacts 169 establishes a holding circuit through conductor 171 so that when the push button switch 155 is released, the solenoid 165 will remain energized.

10 The closure of the contacts 169 will also place the electric signal lamps 158, 159 and the time relay solenoid 172 in parallelism with each other in a circuit which is in parallel with the solenoid 165. The circuit in parallel with the solenoid 165 may be traced from the conductor 163 through the conductor 173 and thence through the lamps 158, 159 and solenoid 172 in parallel to the conductor 174.

20 The lighting of the signal lamps 158 and 159 signals the attendants at the loading station LS and at the pouring station PS that the whole train of flat cars 16 will be started to be moved one car length after a lapse of predetermined time interval. The lighting of the signal lamp 159 is for the purpose of advising the attendant at the pouring station PS that an operation is about to take place in from five to thirty seconds or such time as may be predetermined as sufficient to permit the pouring crew to be in 30 readiness to pour the molten metal into the mold when the flask arrives at the pouring station PS.

When the time relay solenoid 172 is energized, its plunger 175 will be lifted to move upwardly the piston 176 in the dash pot 177. The valve 35 178 will automatically close and the upward movement of the piston 176 will be retarded by the restricted opening 179 in the piston. A switch arm 180 connected to the plunger 175 is located below the contacts 181 and will connect 40 the latter after a predetermined interval of time has elapsed after the signal lamps 158 and 159 have been turned on.

When the contacts 181 are connected, the circuit through the solenoid 162 will be established 45 by means of the conductors 182, 183, 184, contacts 170, and conductor 185. The circuit for the solenoid 162 may be traced from the left-hand terminal of the secondary of the transformer 112, as shown in Fig. 11, through the 50 conductors 113, 163, 173, 182, solenoid 162, conductor 183, contacts 181, conductor 184, contacts 170, conductors 185, 150', contacts 127, and conductors 154, 114 to the other terminal of the secondary of the transformer 112.

55 Energization of the solenoid 162 will effect lifting of the plunger 186 and the closure of the switch contacts 187 and 188 to connect the phase mains 96 and 97 respectively, to the conductors 189 and 190 which are connected to the solenoid 139, as shown in Fig. 12.

Reviewing the sequence of operations, it will be seen that the closure of the push button switch 115 will start the operation of the pump 104, and the operation of this pump may be stopped at 65 any time by the opening of the switch 120. When the pump 104 is in operation, as indicated by the lighting of the signal lamp 125, the closure of the push button switch 155 at the loading station will effect lighting of the signal lamps 158 and 159, respectively, at the loading station LS and at the pouring station PS. After the elapse of a certain time interval predetermined by the setting of the time relay, diagrammatically illustrated in Fig. 11, the solenoid 162 will be energized to effect operation of the solenoid 139 to

move the valve 143 into position to connect the pressure supply to both sides of the piston 56 of the hydraulic reciprocating motor 241. Whenever desired, the emergency switch 156 at the loading station LS may be opened, or the emergency switch 157 at the pouring station PS may be opened, and the opening of either of these switches will effect the de-energization of the solenoid 165 which in turn, by reason of the opening of the contacts 169, 170, will effect de-energization of the solenoids 162 and 172 and the extinguishment of the electric signal lights 158 and 159. Consequently the contacts 187, 188 will be opened, the solenoid 189 de-energized, and the valve piston 143 moved by the spring 141 to the position shown in Fig. 12 to effect automatic return of the piston rod 40 to its initial position.

By means of the volume control valve 185 shown in detail in Fig. 13, the rate of flow into the cylinder 41 to the left of the piston 56, as viewed in Figs. 7 and 11, may be regulated. The pipe 182 of Fig. 11 is connected to the passageway 191 of Fig. 13, and the passageway 192 is connected to the pipe 186. A valve 193 is located in the passageway 192 and may be adjusted by means of the lever 194. A valve 195 controls the flow of the liquid from the passageway 191 to the passageway 192. A piston 196 is connected to the upper end of the valve stem 197, to the lower end of which is connected the valve 195. A spring 198 acts between the cover 199 and the top of the piston 196. A conduit 200 connects the passageway 182 to the chamber 201 above the piston 196.

When the valve 193 is wide open, the rate of flow may be approximately 3.3 gallons per minute at a hydraulic pressure of 650 pounds per square inch, and this gallonage may be varied down to zero by gradually closing the valve 193.

A conduit 202 extends from the passageway 192 to the left of the valve 193 upwardly to a space below the piston 196. It will thus be seen that a differential pressure takes place on the top and bottom of the piston 196 depending upon the extent to which the valve 193 is closed, and this differential pressure will determine the position of the valve 195. When the valve 193 is partially closed, the pressure on the under side of the piston 196 overcomes the pressure on the top of the same to such an extent as to partially close the valve 195 and thus cut down the flow from the pipe 182 to the pipe 186.

By means of the volume control valve 185 the rate of flow through the pipe 55 into the cylinder 41 to the left of the piston 56 may be so regulated as to obtain an infinite speed range. For instance, if the maximum speed of the actuating stroke of the piston rod 40 to move a flat car 16 approximately one car length, is five seconds, such actuating stroke may be slowed down to any speed desired above five seconds. The return stroke, however, will be longer than the maximum actuating stroke and may consume as much as fifteen seconds because the cross-sectional area of the piston rod 40 is small relative to the area of the cylinder 41.

In practice I prefer to provide pumping and electric control facilities for two series of mold conveyers. For instance, one motor 103 may be provided to drive a pump 104 for six mold conveyer hydraulic motors and another motor 110 may be provided for driving another pump 111 for six additional mold conveyer hydraulic motors. The pumps may be interconnected through check valves 203 and 204 to a common relief valve 75

134 as shown in Fig. 11. The relief valve is inserted in the by-pass as a safety valve to protect the pumps and motors.

In some instances either pump 104 or 111 may be found to have sufficient capacity to provide enough volume of flow at full pressure to handle the hydraulic motors 241 of the entire assembly of twelve mold conveyers 15. The second pumping unit would then act only as a standby unit.

In actual practice if it should prove necessary that both pumps 104 and 111 were necessary for securing a forward actuating stroke of each hydraulic motor 241 in five seconds, a shut down of either pump would necessitate increasing the time for the forward actuating stroke of each hydraulic motor 241 to ten seconds.

The pumps 104 and 111 are each preferably of the self-centering type in that each comprises an inner centering device acting automatically to decrease the pump output to the requirements of the limiting factor which is based on twelve feed control valves 137, one of which is shown in Fig. 12. The two pumps 104 and 111 are connected through the check valves 203 and 204 to the single relief valve 134 and the single volume control valve 185 but branch pipes 186', 188' extend from the pipes 182', 188 for connecting the hydraulic motor 241 and the other eleven hydraulic motors in parallel and for connecting all of the electro-magnetic valves including that designated 137 in parallel.

A switchboard panel may be provided for nearly all of the various electrical control devices including one transformer 112, two electro-magnetic switches 102 and 109, two lamps 125 one for the solenoid 117 and the other for the solenoid 117', two electro-magnetic switches 122 one associated with the motor 103 and the other associated with the motor 110, and twelve of each of the electro-magnetic switches 165, time relays 172, electro-magnetic switches 162, limit switches 145, and electro-magnetic valves 137.

There are only two push button switches 115 and two push button switches 120. That is, there is one open push button switch 115 and one closed push button switch 120 associated with each of the electric motors 103 and 110 and these push button switches may be mounted on the switchboard panel.

There are twelve electric lamps 156 and twelve electric lamps 158, respectively located at the loading stations LS and pouring stations PS of the twelve mold conveyers 15. There are twelve each of the electro-magnetic switches 165, time relays 172, electro-magnetic switches 162, limit switches 145 and electro-magnetic valves 137, one of each for each of the mold conveyers 15. There are twelve starting push button switches 155 one for each conveyer and one starting push button may be located, if desired, at the loading station of each mold conveyer.

There are twelve emergency closed push button switches 156, one at the loading station LS of each conveyer and there are twelve emergency closed push button switches 157, one at the pouring station PS of each conveyer 15, as shown in Fig. 1.

From the foregoing it will be understood by reference to Fig. 11 that the electric control circuits to the left of the dashed line DD for the motor 103 are duplicated for the motor 110 and that the group of control circuits to the right of the dashed line DD in Fig. 11 is duplicated

for each of the mold conveyers 15 shown in Fig. 1.

The straight wiring diagram in Fig. 14 shows how the electric motors 103 and 110 may be connected to their respective control circuits and to two series of mold conveyers, each series having two conveyers. However, there may be as many as twelve conveyers with six in each series and only two electric motors one for each series.

The electric control circuits and devices illustrated in Figs. 11 and 14 provide an electric interlock between the electric motors 103 and 110 in that it will be impossible for an operator to close any of the starting push button switches 155 and effect the energization of any of the electro-magnets to the right of the dashed line DD of Fig. 11 without first having either or both of the electric motors 103, 110 in operation. This is because the push button switch 155 depends for its effectiveness on the closure of the corresponding contacts 127 and when the latter are closed, the corresponding motor 103 or 110 is in operation. This electrical interlock prevents burning or overheating of any of the solenoids by reason of prolonged current flow therethrough. It should be understood that the solenoids 165, 172, 162 and 139 are energized for only short periods of time and may therefore be designed for heat radiating capacities accordingly, with increased ampere turns.

The switchboard panels and electric motor pumping units may be distant from the mold conveyers at any convenient location.

By referring to Fig. 14 it will be seen that the supply mains 205 of a three phase alternating current circuit may be connected by means of the main line switch 206 to the mains 96, 97, 98. By closing the main line switches 95 and 105 the motors 103 and 110 are put in readiness to be supplied with current as soon as the switch 102 or 109 or both are closed.

The primary of the transformer 112 is connected between the mains 97 and 98 by closure of the switch 207. By comparing Fig. 11 with Fig. 14 it will be seen that in the latter the control circuits for the motor switches 102 and 109 are connected between the terminals 113 and 114 of the secondary of the transformer 112. The solenoids 117, 122, the contacts 126, the push button switches 115, 120, and the electric lamp 125 are associated with the switch 102 for control of the electric motor 103 whereas the solenoids 117', 122', contacts 126', push button switches 115', 120', and the electric lamp 125' are associated with the switch 109 for control of the electric motor 110. The contacts 127 are closed by energization of the solenoid 122 and the contacts 127' are closed by energization of the solenoid 122'. The contacts 127 and 127' are the interlocking contacts to prevent operation of any of the solenoids to the right of the dashed line DD in Fig. 11 until one or the other or both of the motors 103, 110 are in operation because not until either the contacts 127 or the contacts 127' are closed can the circuit through the transformer secondary be completed by the closure of a starting push button switch 155 at any of the mold conveyer units.

When either the contacts 127 or the contacts 127' are closed the push button switch 155 may be closed to complete the circuit from the conductor 113 through the solenoid 165, switches 155, 156, 157, and limit switch 145.

When the solenoid 165 is energized the con-

tacts 169 are closed and therefore the circuit through the conductor 167 remains closed even after the push button switch 155 is released to open position. The contacts 169 also keep closed 5 a holding circuit for the solenoid 172 and lamps 158, 159 in parallel.

When the time relay 172 closes the contacts 181 the circuit through the solenoid 162 and contacts 186 and 170 will be closed, the contacts 10 having been connected by the energization of the solenoid 165. The energization of the solenoid 162 closes the contacts 187, 188 and consequently the valve magnet solenoid 139 will be energized. As shown at the bottom of Fig. 14 15 the drawing of the current from the mains is balanced by connecting half of the solenoids 139 between the mains 97 and 98, and the other half between the mains 96 and 98.

While in Fig. 14 I have shown the control circuits 167, 183, for only four mold conveyers, it should be understood that the number of such control circuits may be increased to any extent desired within the limits of the capacities of the pumps 104, 111. Any one or more of the mold 20 conveyer reciprocating hydraulic motors may be operated at any time while being supplied with hydraulic pressure medium from either or both of the pumps 104, 111. It may be said that the electric motor 103 is provided with its own control circuit 128 and that the electric motor 110 is provided with its control circuit while each mold conveyer hydraulic reciprocating motor 241 is provided with a separate pair of control circuits 167, 183.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

45. 1. In apparatus of the character described, the combination with an endless train of carriers adapted to travel along a trackway, of hydraulic motor mechanism connected to the train to move the train such distance as to transfer a carrier 50 with a mold thereon from a loading station to a pouring station, valve mechanism for controlling said hydraulic motor, an electro-magnet for operating said valve mechanism to start said motor, a device at the pouring station to signal the attendant at the latter station to be in readiness with the pouring ladle, a time relay for delaying the operation of said electro-magnet and starting of said motor a predetermined length of time after the operation of said signaling device, and 55 circuits and connections controlled by a switch at said loading station for automatically operating said signaling device and enabling said time relay to effect after expiration of said predetermined length of time the operation of said electro-magnet and the starting of said motor to shift the mold carrier to the pouring station.

60. 2. In apparatus of the class described, the combination with a train of carriers, of a hydraulic motor, mechanism adapted to connect said motor to said train to move the train to transfer a carrier from a loading station to a pouring station and at the same time move another carrier to an unloading station, valve mechanism for controlling said motor, electro-responsive means 65 for effecting operation of said valve mechanism,

a switch at the loading station for effecting operation of said electro-responsive means, a signal device for indicating to the attendant at the pouring station that the train is about to be moved, a time relay associated with the electro-responsive means for delaying for a predetermined period of time after operation of the said signal device the starting of said motor to move a carrier from the loading station to the pouring station, and means comprising a switch at the 10 pouring station to render inoperative said electro-responsive means to prevent movement of the train during the pouring operation at the pouring station.

3. In apparatus of the class described, the combination with a train of carriers, of a hydraulic motor, a pump, a hydraulic system connected to said motor and comprising said pump and valve mechanism for controlling said motor, an electric motor for driving said pump, an electro-magnetic switch for controlling said electric motor, electro-responsive means for closing the circuit of said electric motor from the source of electric power, a signal device for indicating the operation of said electric motor and said pump, an electro-magnet for operating said valve mechanism, electro-responsive means for controlling the operation of said valve mechanism electro-magnet, transmission mechanism adapted to connect said hydraulic motor to said train to move a carrier from a loading station to a pouring station in a foundry, means comprising a switch at the loading station for rendering operative said last-named electro-responsive means, signaling means operated by the closing of said last-named switch, a limit switch associated with said hydraulic motor to effect stopping at the pouring station of

5 the carrier moved from the loading station, and an emergency switch at the pouring station to render inoperative the electro-responsive means for operating the valve mechanism until after pouring is completed at the pouring station.

4. Conveying apparatus including a conveyer for moving devices between two operating stations, power mechanism for moving said conveyer in steps, an electric signal and control circuit for said power mechanism including means operable by a starting switch at one station for giving a signal at the second station that said conveyer is about to move, time delay relay means for starting movement of said conveyer after said signal is given a predetermined time and operable automatically in response to actuation of said starting switch, means at said other station for rendering said start switch ineffective, and means for automatically stopping said conveyer after it has traveled a predetermined distance.

5. Conveying apparatus including a conveyer for moving devices between two operating stations, power mechanism for moving said conveyer in steps, an electric signal and control circuit for said power mechanism including means operable by a starting switch at one station for giving a signal at both of said stations that said conveyer is about to move, time delay relay means for starting movement of said conveyer after said signal is given a predetermined time and operable automatically in response to actuation of said starting switch, means at said other station for rendering said start switch ineffective, and means for automatically stopping said conveyer after it has traveled a predetermined distance.

FRED J. WRIGHT.
